UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF NEW JERSEY.

SHEET-DELIVERY MECHANISM FOR PRINTING-MACHINES.

1,078,239.

Specification of Letters Patent.

Patented Nov. 11, 1913.

Application filed March 16, 1911. Serial No. 614,795.

To all whom it may concern:

Be it known that I, HOWARD M. BARBER, a citizen of the United States, and resident of Stonington, in the county of New London and State of Connecticut, have invented a new and useful Improvement in Sheet-Delivery Mechanism for Printing-Machines, of which the following is a specification.

The object of my invention is to provide 10 novel means for insuring the delivery of the sheets from a sheet delivery cylinder on to a sheet receiving table.

In cases where sheets are delivered directly from a delivery cylinder on to a sheet 15 receiving table, it has been previously necessary to provide more or less complicated means for insuring the proper delivery of the said sheets. This is especially true where the sheets are delivered successively with 20 only a slight space separating each sheet from the following one.

This present invention is directed to a very simple arrangement for insuring the proper delivery of the sheets, said arrangement including an air blast directed against 25 each sheet from the inside of the delivery cylinder in a way to force the back edge of the sheet which has by far the greater distance to fall from the cylinder, away from 30 the cylinder so that the back edge of the sheet will not interfere with the delivery of the next succeeding sheet.

A practical embodiment of the invention is represented in the accompanying drawings, in which,

Figure 1 represents a sheet delivery mechanism in side elevation, Fig. 2 is a longitudinal vertical section through the same, Fig. 3 is a partial front view of the mechanism, 40 Fig. 4 is a detail view of the geared connection between the several operative parts, and Fig. 5 is a detail view showing the means for opening the grippers on the transfer cylinder at proper times to receive the sheets 45 from the cutters and transfer the same to the delivery cylinder grippers.

The rotary cutters for severing the sheets from the web are denoted by 1, 1*, the transfer cylinder for receiving the sheets from 50 the cutters and transferring them to the delivery cylinder, is denoted by 2, the delivery cylinder is denoted by 3, and the sheet receiving table is denoted by 4. In the present instance the rotary cutters 1, 1* are provided with three sets of co-acting blades 5,

the transfer cylinder is shown as provided with two sets of grippers 6 and the delivery cylinder 3 is shown as provided with four sets of grippers 7. The rotary cutters are driven together by intermeshing gears 8, 9. 64

The delivery cylinder is made hollow and an axially arranged air blast pipe 10 enters the cylinder through one of its hollow gudgeons 11. This axially arranged air blast pipe is provided within the cylinder with a 65 plurality of nozzles 12 arranged to direct blasts of air successively through slots 13 through the walls of the delivery cylinder 3, at points spaced from each set of grippers 7. This axially arranged pipe 10 is connected 70 by a pipe connection 14 with any suitable source of air pressure supply, such for instance, as a power actuated blowing engine 15.

The geared driving connection between 75 the several parts is as follows: A gear 16 on one fan shaft 17 of the blower 15, meshes with a gear 18 which in turn meshes with a gear 19 fixed on a shaft 20. A gear 21 on the shaft 20 meshes with a gear 22 on the 80 shaft 23 of the transfer cylinder 2. This gear 22 meshes with a gear 24 fixed on the shaft 25 of the delivery cylinder 3. A second gear 26 fixed on this delivery cylinder shaft 25, meshes with a gear 27 which in turn meshes with a gear 28 fixed on the shaft 85 29 of the rotary cutter 1.

A stationary cam 30 is arranged in position to open each set of grippers 6 on the transfer cylinder 2, by engaging a stud 90 roller 31 on a lever 32, of each set of grippers. A spring 33 serves to hold the grippers normally closed. This cam 30 is arranged to open the grippers 6 to receive the sheets from the rotary cutters and also opens 95 the grippers to deliver the sheets to the delivery cylinder grippers 7. In the present instance the cam 30 is shown as arranged to open the grippers 6 to deliver the sheets to the delivery cylinder grippers and keep the 100 said grippers 6 open until they have received the sheets from the rotary cutters.

A stationary cam 34 is arranged to open 105 the delivery cylinder grippers 7 for receiving the sheets from the transfer cylinder grippers and for opening the grippers 7 to deliver the sheets on to the sheet receiving table 4. This cam 34 is arranged to engage a stud roller 35 on the lever 36 of each set of grippers 7, a spring 37 being used for 110

holding the grippers normally closed. In the present instance the cam 34 is arranged to open the grippers 7 at the point of delivery and keep the grippers open until a sheet 5 has been delivered thereto from the transfer cylinder.

The sheet receiving table 4 may be provided with any well known or approved jogging mechanism and no specific description 10 thereof will be made herein as it forms no part of the present invention.

In operation, as the sheets are brought down into position to be delivered on to the sheet receiving table 4, the blasts of air 15 through the nozzle 12 will be directed through their respective slots 13 against the back edges of the sheets, thus forcing the back edges away from the periphery of the cylinder so that when the grippers 7 open to 20 release the advance edges of the sheets, the sheets will be delivered quickly and freely on to the sheet receiving table, thus making way for the next succeeding sheet and permitting a very rapid delivery of the sheets 25 from the delivery cylinder.

By the term "cylinder" I intend to cover any operative device for carrying the sheets through the prescribed paths and by the term "table" I intend to cover any surface 30 for receiving the sheets.

It is evident that various changes might be resorted to in the construction, form and arrangement of the various parts without de-

parting from the spirit and scope of my invention; hence I do not wish to limit myself 35 strictly to the structure herein set forth, but

What I claim is:

1. A sheet delivery mechanism including a rotary hollow cylinder arranged to deliver the sheets at a predetermined point, said cylinder having slots through its walls, and a stationary device located within the cylinder arranged to direct a blast of air through said walls against the back edges of the sheets for blowing the same away from the 45 cylinder as the sheets are delivered.

2. A sheet delivery mechanism including a rotary hollow cylinder arranged to deliver the sheets at a predetermined point, said cylinder having a plurality of sets of grippers 50 around its periphery and a plurality of slots through the walls of the cylinder between said sets of grippers and a stationary device arranged to direct successive blasts of air through said slots for blowing the sheets 55 away from the cylinder as they are delivered.

In testimony, that I claim the foregoing as my invention, I have signed my name in presence of two witnesses, this twenty-third 60 day of February A. D. 1911.

HOWARD M. BARBER.
